(57) **CLAIM**

The ornamental design for a bowl, as shown and described.

DESCRIPTION

FIG. 1 is a top, front and left isometric view of a first embodiment of a bowl showing our new design;

FIG. 2 is a bottom, front and right isometric view thereof;

FIG. 3 is a top plan view thereof;

FIG. 4 is a bottom plan view thereof;

FIG. 5 is a front elevation view, the rear, left and right side views being identical thereto;

FIG. 6 is a cross-sectional view taken along line 6-6 of FIG. 3;

FIG. 7 is a top, front and left isometric view of a second embodiment of a bowl showing our new design;

FIG. 8 is a bottom, front and right isometric view thereof;

FIG. 9 is a top plan view thereof;

FIG. 10 is a bottom plan view thereof;

FIG. 11 is a front elevation view, the rear, left and right side views being identical thereto;

FIG. 12 is a cross-sectional view taken along line 12-12 of FIG. 9;

FIG. 13 is a top, front and left isometric view of a third embodiment of a bowl showing our new design;

FIG. 14 is a bottom, front and right isometric view thereof;

FIG. 15 is a top plan view thereof;

FIG. 16 is a bottom plan view thereof;

FIG. 17 is a front elevation view, the rear, left and right side views being identical thereto; and,

FIG. 18 is a cross-sectional view taken along line 18-18 of FIG. 15.
